No. 627,061.

Patented June 13, 1899.

J. HOCK.
FOLDING COT.

(Application filed May 6, 1898.)

(No Model.)

UNITED STATES PATENT OFFICE.

JOHN HOCK, OF ALLEGHENY, PENNSYLVANIA.

FOLDING COT.

SPECIFICATION forming part of Letters Patent No. 627,061, dated June 13, 1899.

Application filed May 6, 1898. Serial No. 679,898. (No model.)

To all whom it may concern:

Be it known that I, JOHN HOCK, a citizen of the United States of America, residing at Allegheny, in the county of Allegheny and State 5 of Pennsylvania, have invented certain new and useful Improvements in Folding Cots, of which the following is a specification, reference being had therein to the accompanying drawings.

10 My invention relates to certain new and useful improvements in folding cots.

The object of my invention is to provide a folding cot which when folded forms a small and compact package and occupies but a small 15 amount of space.

A still further object of my invention is to provide a folding top for said cot which is adapted to be movably connected thereto and when not in use can be rolled, and thereby 20 form a compact package.

My invention further consists in the novel construction, combination, and arrangement of parts hereinafter fully described, illustrated in the accompanying drawings, and 25 particularly pointed out in the claims.

In the drawings, Figure 1 is a perspective view of my improved folding cot with a part of the slatted top broken away. Fig. 2 is a top view of one of the side rails, the end rails 30 folded thereon. Fig. 3 is a side view showing the parts assembled against one of the side rails. Fig. 4 is a side view of one end of the side rails and one of the legs or supports, showing rigid braces secured thereto. 35 Fig. 5 is a perspective view of one of the braces.

Like figures of reference indicate corresponding parts throughout the several views of the drawings, in which—

40 1 and 2 indicate the side rails, and 3 and 4 the end rails, which are constructed, preferably, of wood, although iron or steel may be used, if desired. The side rail 1 is connected to the end rails by the hinges 5, and the end 45 rails are adapted to fold against the inner side of the side rails. The side and end rails are provided with a mortise and tenon, as shown at 6 and 7, for securing the same together when the cot is set up. Formed in 50 the side rails are slots 8, which are adapted to receive the upper ends of the legs or supports 9 and secure the same in position. The

legs or supports 9 are hinged at 10 to the side rails and are adapted to fold against the same. The legs or supports are provided with braces 55 11. The braces 11 are secured to each side of the legs or supports, at their upper and lower ends, by pivots 12 and are in an inclined position. Pivoted to the bottom of the side rails, as at 14, are rigid braces 60 15, having hooks 16 formed on their free end, which connect with eyelets 17, attached to the legs or supports for holding them rigidly in position.

My adjustable folding top consists of a series of slats 18, secured together by strips of webbing 19, suitably secured to the under face thereof. Attached to the ends of said slats, as at 20, are web-loops 21 for removably and adjustably securing the top or a series of said slats to the end rail.

The operation of my improved folding cot can be readily understood from the foregoing description and the accompanying drawings.

It will be noted that various changes may 75 be made in the details of construction without departing from the general spirit of my invention.

Having thus described my invention, what I claim as new, and desire to secure by Letters 80 Patent, is—

1. A folding cot having a frame consisting of two side rails and two end rails suitably connected together, said end rails being also hinged at their one end to one of the side 85 rails and adapted to fold in alinement therewith when disconnected from the opposite side rail, a folding top consisting of a series of slats, loops connecting said slats to the end rails, supporting-legs formed with a tenon on 90 their upper ends to engage a mortise provided therefor in the side rails, pivoted braces connecting said supporting-legs, braces rigidly connecting said supporting-legs to the side rails, said legs being also hinged to said side 95 rails to permit their folding in alinement therewith when the rigidly-connecting braces are disengaged from the said side rails, substantially as herein shown and described.

2. A folding cot consisting of side and end 100 rails suitably secured together, a folding slatted top, loops secured to the ends of the slats of said top and adapted to adjustably secure said top to the end rails, legs or sup-

ports being hinged to said rails, the upper ends of said legs or supports being adapted to engage apertures formed in said side rails, incline braces securing the legs or supports together in pairs, and rigid braces pivotally secured to said side rails and to the legs or supports thereby rigidly securing the legs or supports in position when the cot is in the

open position, substantially as shown and described. 10

In testimony whereof I affix my signature in the presence of two witnesses.

JOHN HOCK.

Witnesses:

A. M. WILSON,
Wm. A. WAY.
